UNITED STATES PATENT OFFICE.

ADALBERT LISKOWACKI, OF DETROIT, MICHIGAN.

DESIGN FOR A STANDARD.

59,664.

Specification for Design.

Patented Nov. 15, 1921.

Application filed February 25, 1921. Serial No. 447,886. Term of patent 3½ years.

To all whom it may concern:

Be it known that I, ADALBERT LISKOWACKI, citizen of Poland, residing at Detroit, in the county of Wayne and State of Michigan, have invented a new, original, and ornamental Design for Standards, of which the following is a specification, reference being had to the accompanying drawing, forming a part thereof.

The figure is a perspective view of my standard, showing my design.

I claim:

The ornamental design for a standard, substantially as shown.

ADALBERT LISKOWACKI.
